[57] CLAIM

The ornamental design for an atomizer, as shown and described.

DESCRIPTION

FIG. 1 is an exploded perspective view of an atomizer showing my new design;

FIG. 2 is a plan view of the atomizer, viewed from above as shown in FIG. 1 with the transparent top cover removed;

FIG. 3 is a front elevational view of the atomizer as shown in FIGS. 1 and 2 with the transparent top cover removed;

FIG. 4 is a plan view of the atomizer, viewed from above with the transparent top cover disposed in place; FIG. 5 is a front elevational view of the atomizer as shown in FIG. 1 with the transparent top cover disposed in place;

FIG. 6 is a left side elevational view thereof, the right side being a mirror image;

FIG. 7 is a rear elevational view of the atomizer as shown in FIGS. 5 and 6; and

FIG. 8 is a plan view of the atomizer, viewed from below as shown in FIG. 5.
